UNITED STATES PATENT OFFICE.

HENRY HOWARD, OF BROOKEVILLE, MARYLAND.

DRAFTING AND PLOTTING INSTRUMENT.

1,090,064.

Specification of Letters Patent. Patented Mar. 10, 1914.

Application filed December 12, 1913. Serial No. 806,299.

To all whom it may concern:

Be it known that I, HENRY HOWARD, a citizen of the United States, residing at Brookeville, in the county of Montgomery and State of Maryland, have invented certain new and useful Improvements in Drafting and Plotting Instruments; and I hereby declare that the following is a full, clear, and exact description thereof, reference being had to the accompanying drawings, which form part of this specification.

This invention is a novel improvement in drafting and plotting instruments and its object is to provide a very convenient tool whereby figures of any desired outline can be accurately and quickly plotted, and which can be used as a drafting tool in place of a T-square and angle, and can be also used as a section lining tool; and whereby by alternately fastening the two end members to the board or surface on which it is being used the tool can be shifted anywhere over a large area of surface, and an exact relation between the end members of the instrument will be maintained.

The implement in brief comprises a protractor, a triangle and an L-square; and parallel links connecting the straight edge of the protractor with one leg of the triangle and forming therewith a parallelogram; and parallel links connecting the other leg of the triangle with one leg of the L-square and forming therewith another parallelogram, so that if the protractor be attached to a board the L-square will always be held at any predetermined angle to a given perpendicular or horizontal line in any position to which it can be moved, as permitted by the intermediate connections; or if the L-square be fastened to the board the protractor will be held at the same relative angle thereto and in whatever position it can be shifted as permitted by the intermediate connections. When used on large surfaces after the protractor or L-square is adjusted to the desired angle, and one of these members fastened, such angle will be constantly maintained by the other member and the instrument can be shifted along the surface from top to bottom, or from end to end, by fastening the L-square to the board before the protractor is loosened (or vice versa) and then loosening the latter and bringing it up to the square (or vice versa) and fastening it before releasing the T-square.

A further object of the invention is to so

construct the parts that there will be a minimum of wear at the joints or pivots of the parts; and I also provide means for compensating for any such wear so that the instrument can be used indefinitely and will maintain its accuracy.

I further provide means whereby the implement may be used for cross sectioning in a simple and accurate manner to insure uniformly spaced parallel section lines.

I will explain the invention with reference to the accompanying drawings in which—

Figure 1 represents a view of the complete implement. Fig. 2 is an enlarged section through one of the joints, on line 2—2, Fig. 1. Fig. 3 is a detail section through the compensating device, on line 3—3, Fig. 1.

The protractor 1 may be of ordinary form and construction having a straight edge and a scale as usual; the triangle 2 may also be of ordinary construction; and so may the L-square 3. The straight bar 1^a of the protractor is connected to one of the sides of the triangle 2 by parallel links 4, which links are pivoted to the protractor as at 4^a and to the triangle as at 4^b. Preferably these rivets are hollow as shown so as to increase the wearing surface of the pivot and also to afford a convenient means for the insertion of thumb tack points through the hollow rivets 4^a to fasten the protractor in place.

One leg of the L-square 3 is similarly connected by parallel links 5 to the leg of the triangle at right angles to that leg to which the links 4 are attached. The links 5 are connected to the leg of the L-square 3 by means of tubular rivets 5^a so that thumb tacks can be inserted therethrough, and the links 5 are also preferably connected to the triangle 2 by hollow rivets 5^b. The ends of the links 4 and 5 at the apex of the triangle are connected by the same rivet 5^c. It will be seen that practically all the links are in the same plane, and this is an important practical feature of the construction of the device. The links being of the same length it follows that the leg 3^e of the L-square will always stand parallel with the straight edge 1^e of the protractor no matter in what positions these parts may be adjusted; consequently the angle with respect to a given line at which the leg 3^e of the L-square is to be used can be readily determined by correspondingly shifting the protractor with respect to such line. Any desired angle can be readily calculated on the protractor

by means of the scale thereon, which can be read in the usual manner, and the straight edge of this protractor has a notch 1^a which is disposed at the axis of the protractor and by sticking a pin in said notch or making a mark with a pencil in said notch and at the proper point on the curved edge 1^c of this protractor and drawing a line on the surface between said points, the angle at which the L-square is set relative to any given perpendicular can be determined and maintained by adjusting the edge 1^c of the protractor to said line. Similarly the arm 3^e of the square can be placed on any given line as a base or perpendicular or as a line of latitude or longitude and the protractor secured rigidly in place on the board by inserting thumb tacks through the tubular rivets, and such arm of the L-square will then always maintain the same true parallel relation to the said line, no matter to what point on the surface it may be moved.

To compensate for any lost motion or possible wear on the rivets I provide each parallelogram with an automatic take-up device, which comprises a sectional link 6 arranged between the protractor and angle, and a similar link 7 arranged between the angle and L-square. The links 6 and 7 are each composed of two sections, one of said sections has a screw socket 6^b on its meeting end beside an eye 6^c on the meeting end of the opposite section; through this eye passes a screw 6^d that is tapped into the socket, and a helical expansion spring 6^e is interposed between the eye and the head of the screw, thus making an adjustable spring-tensioned link, which automatically takes up any looseness or wear of the pivots, and keeps the protractor and angle held uniformly distanced by the links 4 and keeps the L-square and triangle held uniformly distanced by the links 5. The take-up links 6 and 7 are preferably connected to the protractor triangle and square by tubular pivots, and are arranged in a median line between the parallel links.

When using the implement as a section liner, a bar 8 is employed, said bar having perforations 8^a in its ends for the passage of thumb tacks, and having its side edges serrated, and after the L-square has been set to the desired angle of the section lines, and the protractor fastened to the surface; said bar 8 is secured beside the L-square, as shown in Fig. 1, adjacent the part to be section lined, in such position that a serrated edge of this bar can be contacted by the apex or point of one of the ends of the L-square. This bar 8 is provided with equally spaced serrations on its sides, the serrations on its opposite sides being of different depth or width, and by successively engaging the L-square with the notches in the side of said bar the L-square

can be used for section lining in the manner known to draftsmen; and the section lines will be uniformly spaced apart according to the distance apart of the adjacent notches in the bars 8.

The invention practically provides three instruments in one. Angles can be marked off by the protractor without any adjustment; and deflections right and left can be taken direct from the protractor without any adjustment. When the protractor is to be used the L-square should be fastened, and when the L-square is to be used the protractor should be fastened; and they can be used alternately on the same surface and their predetermined relation to any given horizontal or perpendicular maintained by simply fastening one before releasing the other; and when thus used they never lose the desired angular relation no matter to what positions on the surface they may be shifted. The instrument can be readily used as a section liner by attaching bar 8, or its equivalent, to the surface to be section lined, and using the implement in connection therewith as above described.

I preferably use the L-square and the ends of this square are beveled as indicated at 3^a at an angle of 45° to its sides, and also at right angles to the hypotenuse 2^a of the triangle 2 so that any time it is desired to draw a line at right angles to said hypotenuse, or to the hypotenuse of the triangle formed by the legs of the L-square, such line can be obtained by drawing a line along the hypotenuse of the triangle and a line across the points of the L-square while the parts are held stationary. The hypotenuse 2^a of the triangle 2 always stands at an angle of 90° to a line drawn between the points or hypotenuse 3^a of the L-square. This angle of 90° between the hypotenuse of the triangle and a line drawn between the points of the L-square would be maintained in all positions of the parts, and this feature of the instrument is of great practical convenience and renders the triangle an efficient and important part of the instrument.

What I claim is:

1. In an instrument of the character specified, the combination of a protractor, an intermediate member and a square, parallel links connecting the protractor and intermediate member, and parallel links connecting the square and intermediate member, the pivots connecting said links to the square and to the protractor being tubular for the insertion of devices for attaching the same to a surface.

2. The combination of a protractor, a square and an intermediate member, parallel links pivotally connecting the protractor with the intermediate member, parallel links pivotally connecting said intermediate member to the square, and devices connecting the

protractor and member and the member and square to compensate for lost motion and wear on the pivots.

3. The combination of a protractor, a square and an intermediate member, parallel links pivotally connecting the protractor with the intermediate member, and parallel links pivotally connecting said intermediate member to the square, and a compensating link connected to the protractor and intermediate member between their parallel connecting links, and a similar compensating link connecting the triangle and square between their parallel connecting links.

15 4. The combination of a protractor, a square and an intermediate member, parallel links pivotally connecting the protractor with the intermediate member, and parallel links pivotally connecting said intermediate member to the square; and intermediate spring links between the parallel links for compensating for wear on the pivots, said parallel links being attached to the protractor and to the triangle by tubular rivets, for the engagement of fastening devices.

5. The combination of a protractor, a square, and an intermediate member, parallel links pivotally connecting the protractor with the intermediate member, and parallel links pivotally connecting said intermediate member to the square, said connecting links being attached to the protractor and to the triangle by tubular rivets; with a com-

sating device connected to the protractor and intermediate member between the parallel links, and a similar compensating device connected to the intermediate member and square between their connecting parallel links, substantially as described.

6. In an implement of the character specified, the combination of a protractor, a triangle and an L-square, parallel links connecting the protractor and triangle, and parallel links connecting the triangle and L-square, the pivots connecting said links to the L-square and to the protractor being tubular for the insertion of fastening devices for attaching the same to the surface.

7. The combination of a protractor, an L-square and an intermediate triangle, parallel links pivotally connecting the protractor with the triangle, and parallel links pivotally connecting said triangle to the L-square, a sectional spring link connected to the protractor and triangle intermediate the parallel links, and a similar link connected to the triangle and L-square intermediate their parallel connecting links, substantially as and for the purpose described.

In testimony that I claim the foregoing as my own, I affix my signature in presence of two witnesses.

HENRY HOWARD.
